JOSEPH JANDASEK, OF CICERO, ILLINOIS

METHOD AND APPARATUS FOR COMPRESSING GASES

Application filed March 15, 1926. Serial No. 94,846.

This invention relates to a new method and apparatus for compressing gas or air by the action of fluids influenced by centrifugal force.

5 In contra-distinction to present known methods and apparatus for compressing air or gases, the method and apparatus herein contemplated utilizes the action of a fluid influenced by centrifugal force, which fluid 10 is retained in a revolving body.

The operation of the apparatus herein described is similar to that of known hydraulic air compressors wherein the pressure due to gravity increases downwardly, the difference 15 being in the utilization of centrifugal force of a rotating fluid body wherein the pressure increases toward the periphery thereof.

It is an object of the invention to provide a new and useful compressor embodying 20 novel features of construction wherein the action of a fluid influenced by the centrifugal force of said fluid, will uniformly compress the air or gas.

It is also an object of the invention to provide 25 certain details and novel features of construction tending to increase the general efficiency of compressors of this particular type and character.

To these and other useful ends my invention consists in the matters hereinafter set forth and claimed.

In the accompanying drawings:

Figure 1, is a longitudinal section through a compressor embodying my invention;

35 Figure 2, is an enlarged detail of a section of the compressor showing the gas or air inlet connection; and

Figure 3, is a cross section taken on line 3-3 of Figure 2, showing the segmental gas 40 feeder chamber and relative position of the rotating inlet passages.

Figure 4, is an enlarged cross section of one of the gas inlet pipes;

Figure 5, is a cross section of the stationary deflecting vanes taken on line 5-5 of Figure 1;

Figure 6, is a cross section taken on line 6-6 of Figure 1, showing the portions and gas inlet pipes within the revolving drum.

50 Figure 7, is a diagrammatic illustration

showing the relative position of the stationary deflecting vanes and the revolving vanes;

Figure 8, is a diagrammatic longitudinal section showing the application of my invention to a single stage double flow unit;

55

Figure 9, is also a diagrammatic longitudinal section showing the application of my invention to a double stage unit for high compression uses.

The apparatus consists preferably of a 60 drum 12 supported for rotation on the shaft 13. The drum 12 contains water or any other suitable fluid which circulates within the drum during its rotation.

The drum 12 is preferably formed of two 65 half sections 12^A and 12^B bolted together about the peripheral joint 12^C.

The half section 12^A is divided into six 70 equally spaced compartments by straight partition walls 12^D as shown in Figures 1 and 6. The other half section 12^B is also divided into similar corresponding compartments by walls 12^E, 12^F, and 12^G. The straight walls 12^D being in alignment with the walls 12^E 75 and extending from the junction of the half sections 12^A and 12^B to the line 12^{E'}. The partition walls 12^F, however, are slightly curved as shown in Figure 1, and extend from their meeting line 12^{E'} to close proximity of the stationary vanes 16^A within the distance 80 indicated by "X" in Figure 1.

The partition walls 12^G are still further curved and in opposite direction to the walls 12^F and extend within the distance indicated by "Z" in Figure 1.

85

The shaft 13 is rotatably supported in the bearing 21 at one end and in bearing 22 at the other end. The overhanging extension 13^A of the shaft is adapted to support a pulley or gear or chain sprocket for purpose of 90 receiving rotary action from any suitable engine or motor.

The base portions of the bearings 21 and 22 are formed integrally with the supporting frame 23, the base 23^B and legs 23^A of 95 which are hollow to provide an interior enclosed chamber 23^C which is filled approximately to the level "Y" with the same liquid within the drum 12.

A suitable pipe 27 is provided which com- 100

5 municates at one end with the liquid reservoir 23^c and at the other end with the interior of the drum 12 for the purpose of automatically supplying liquid into the drum 12 should for any reason, such as evaporation, the proper amount be decreased.

10 The gas inlet pipe 25 is provided with a control valve 26 and discharges the gas under atmospheric or less than atmospheric pressure into the segmental chamber 22^a formed within the inner end of the bearing 22. The chamber 22^a communicates intermittently and successively with the inlet openings 27 which are formed in hub of the drum casting 12^a and connected by the tubular branch pipes 14^a with the gas inlet pipes 14.

20 The gas or air passing through the series of inlet pipes 14 which project into the narrow mouth 15^a of the interior passages 15 will cause a number of small jets of gas to be entrained by the liquid flowing past them within the decreased area of the fluid passages 15^a. In other words, the increased velocity 25 of the liquid flowing around the inlet pipes 14 will cause a Venturi effect and thus draw the air or gas into admixture with the fluid.

30 The portions of the pipe 14 within the passages 15^a are slightly altered in cross section as clearly seen in Fig. 4, that is, they are flattened and the ends are closed so that the gas is discharged only from the small openings 14^b located in the tops of the pipes when viewed from the periphery of the drum 12. 35 Due to the intermittent discharge of gas, a more homogeneous mixture of fine bubbles is obtained.

40 The mixture of gas and fluid moves obviously toward the periphery due to centrifugal force for gradual compression.

45 The deflection of the liquid due to the curve in the wall 12^b, in connection with the gradually enlarged interior 15^b at the periphery of the drum 12 will change the direction of the flow of the mixture, and increase the pressure at the periphery to thus cause a total separation of the gas from liquid. The gas accumulating in the pocket 15^c.

50 It may be stated that the flow of the mixture in the enlarged peripheral passage 15^b is parallel to the axis of the rotation of the drum 12, hence with the decreased velocity ample time is allowed for the gas bubbles to escape into the pocket 15^c.

55 The fluid alone then passes into the passage 15^d toward the axis of rotation, thus maintaining upon the air or gas to be compressed, a pressure due to height "h" of the liquid column which is measured perpendicularly 60 to the revolving shaft in the passage 15^d. It is now obvious that the passage 15 is filled with a lighter mixture of gas and liquid while the passage 15^a contains a heavier fluid. Hence, the height of mixture at "j" must be 65 great enough to balance the counter-acting

height of the liquid at "h" to cause enough over-pressure to keep the liquid in circulation, to thereby compress the gas or air at the periphery of the drum. In order to accomplish this balance, stationary arcuate 70 vanes 16^a are interposed at the inner or discharge ends of the passages 15^d to reduce or diminish the action of the centrifugal force whereby the force in the channels 15 will overcome the force in the channels 15^d. 75

The vanes 16^a are formed integrally with and between the outer frusto-conical wall 16^b and the inner frusto-conical wall 16^d. The inner end of the wall 16^d is formed integrally with the tubular extension 16^c. The entire 80 stationary vane unit is designated by numeral 16 and is supported in stationary position on the shaft 13 by means of a brake shoe 17 and tightening screw 18 having a hand wheel 19. The screw 18 is supported in the 85 arm 20 formed integrally with the cap of the bearing 21. Should the operator desire to temporarily stop the compression of the gases, the same can be attained by simply loosening the screw 18 to disengage the brake 90 shoe from the extension 16^c to permit the stationary vane cone 16 to revolve with shaft 13 and drum 12 thus stopping the circulation of the liquid and compressing action.

95 The vanes 16^a are disposed within the cone 16 at an angle to the flowing liquid to decrease any impedance effect which might arise from any abrupt resistance, and further, to decrease any variations or fluctuations in the flow of the liquid. Having 100 passed the vanes 16^a, the fluid moves into the narrow inlet mouth 15^a, and another cycle of mixing, compressing and separating takes place. In this manner, the fluid is continually reused during the continuous operation 105 of the machine.

110 The compressed gas which has been compressed in the annular chamber 15^c is discharged through the pipes 23 into the passage 13^c of the shaft 13, and through the check valve 24, into storage or for direct use. Suitable coils 23^a may be formed in the pipes 23 for cooling of the compressed gas. The drum section 12^a is preferably formed with openings 30 within the double walls 115 thereof to permit the entrance of air to cool the coils 23^a.

120 It may here be noted that while it takes approximately a 34 foot head of water to produce a pressure of 1 atmosphere by gravity, the same can be readily attained by my apparatus with a "height" which is comparatively much less due to the centrifugal force maintained by a predetermined rotation of the drum. Furthermore, as the gas 125 in my apparatus is compressed isothermally at the temperature of the liquid, less power will be required than in any reciprocating type of compressor.

130 The above described machine may be

termed, a single flow, one stage machine. It is readily apparent that in order to save space and balance the axial thrust, the same machine can be built in the form of a double flow type, as shown diagrammatically in Fig. 8, in which the arrows indicate the circulation of the mixture and gas.

Also, the machine may be designed as a high pressure type, and still maintain the drum of a comparatively small diameter, by arranging a plurality of drums in adjacent positions affording successive stages of compression as for instance, in steam turbines. Such arrangement is shown diagrammatically in Fig. 9.

I claim:

1. A compressor comprising a revolving drum, a liquid in said drum, means for conveying gas into said drum for admixture with said liquid during the rotation of said drum, means causing the circulation of said liquid in said drum during its rotation, means for separating said gas from said liquid under compression within said drum by the centrifugal force of said liquid, and means to permit the discharge of said compressed gas from said drum.

2. A compressor comprising a revolving drum, a liquid in said drum, means for intermittently conveying a stream of gas into said drum for admixture with said liquid, means causing the circulation of said liquid in said drum during its rotation, means for separating said gas from said liquid under compression within said drum by the centrifugal force of said liquid, and means to permit the discharge of said gas from said drum.

3. A compressor comprising a revolving drum, a liquid in said drum, means for intermittently conveying a plurality of streams of gas into said drum for admixture with said liquid, means causing the circulation of said liquid in said drum during its rotation, means for separating said gas from said liquid under compression within said drum by the centrifugal force of said liquid, and means to permit the discharge of said gas from said drum.

4. A compressor comprising a revolving drum, a plurality of compartments within said drum, a liquid within said compartments, a gas chamber adjacent said drum, a plurality of inlet passages leading into said drum compartments, means for intermittently drawing the gas from said gas chamber through said inlet passages into said compartments for admixture with said liquid, stationary vanes interposed within said compartments causing the circulation of said liquid during the rotation of said drum, means at the outer portion of said drum for changing the direction of the flow of the mixture of said liquid and gas and retarding its speed to cause a separation of said gas from said liquid under

compression within said drum by the centrifugal force of said liquid, and means to permit the discharge of said compressed gas from said drum.

5. A compressor as embodied in claim 4, and including said inlet passages with flattened discharge ends having openings for the discharge of the gas.

6. A compressor comprising a rotatable shaft, a revolving drum mounted on said shaft, a liquid within said drum, said drum having an inner wall and an outer wall with a passage between said inner and outer walls for said liquid and a plurality of transverse walls integral with said inner and outer walls, an annular depression in said inner wall forming an annular chamber of segmental cross section within said drum passage, a plurality of gas inlet passages extending into said fluid passage within said drum, means for intermittently discharging the gas through said gas passages for admixture with said fluid, means for inducing a circulation of said fluid during the rotating of said drum, means for separating the gas from said fluid whereby said gas will be collected within said annular chamber, said shaft having a longitudinal passage within one end thereof, and a tube leading from said annular gas chamber to said longitudinal passage within said shaft for discharging the compressed gas therethrough.

7. A compressor as embodied in claim 1 and including means for affecting said means causing the circulation of the liquid in said drum whereby the circulation of said liquid will be stopped during the continued rotation of said drum.

8. A compressor as embodied in claim 4 and including means for releasing said stationary vanes to permit their rotation with said drum to thereby stop the circulation of the liquid and the compression of the gas.

9. A compressor comprising a double drum forming a revolving unit, a single shaft for said unit drum, said unit drum having outer end passages therein communicating with an enlarged peripheral passage, a common central passage communicating with said peripheral passage and a branch passage leading from said central passage to said outer passages, a liquid within said passages, means for causing a circulation of said liquid through said outer end passages to the peripheral passage into said common central passage and thence through said branch passage back to said outer end passages, means for admitting gas or air into said outer passages for admixture with said circulating liquid during the rotation of said unit drum, means for separating the gas or air from the liquid within the peripheral passage and compressing same therein under centrifugal force of said liquid, a pair of annular chambers within said peripheral passages adapted to receive the

- compressed air or gas, said shaft having a longitudinal passage in each end thereof, and passages leading from said annular gas chambers to said longitudinal shaft passages for discharging the compressed air or gas there-through.
10. A compressor as embodied in claim 9, and including said means for admitting the gas or air into said outer passages comprising flattened discharge ends having a plurality of comparatively small openings for affording the withdrawal of the gas or air into admixture with the circulating liquid.
11. A two-stage compressor comprising a double drum forming a revolving unit, a single shaft for said unit drum, said drum having a partition wall dividing the interior thereof into two separate compartments one for the first stage compression and the other for the second stage compression, a liquid in said compartments, means causing a circulating of said liquid within said compartments during the rotation of said drum, means for admitting gas into the first stage compression compartments near the longitudinal axis of said drum for admixture with the circulating liquid in said compartment during the rotation of the drum, means for separating the gas from the liquid during compression within the peripheral passage of said first stage compartment, an annular gas chamber within each of said compartments for receiving the compressed gases, means for conveying the compressed gas from the gas chamber of said first stage compartment into the second stage compartment for admixture with the circulating liquid therein, means for separating the gas from the liquid during compression within the peripheral passage of the second stage compartment, a longitudinal passage within the end of said shaft adjacent said second stage compartment, and means for conveying the compressed gas from the annular gas chamber of said second stage compartment into said longitudinal passage in said shaft for discharge therefrom.
12. The method of compressing gases which includes the steps of imparting a rotary motion to a confined body of liquid, causing a circulation of said liquid in its confined state during the bodily revolution thereof, passing a stream of gas into said body of liquid for admixture with said revolving and circulating liquid, retarding the body of circulating mixture of gas and liquid during its revolution and compressing the gas by the centrifugal pressure of said revolving liquid.
13. The method of compressing gases which includes the steps of imparting a rotary motion to a confined body of liquid, causing a circulation of said liquid in its confined state during the bodily revolution thereof, passing a plurality of streams of gas into said body of liquid for admixture with said revolving and circulating liquid, retarding the body of circulating mixture of gas and liquid during its revolution and compressing the gas by the centrifugal pressure of said revolving liquid.
14. The method of compressing gases which includes the steps of imparting a rotary motion to a confined body of liquid, causing a circulation of said liquid in its confined state during the bodily revolution thereof, intermittently passing a plurality of streams of gas into said body of liquid for admixture with said revolving and circulating liquid, retarding the body of circulating mixture of gas and liquid during its revolution and compressing the gas by the centrifugal pressure of said revolving liquid.
15. The method of compressing gases which includes the steps of imparting a rotary motion to a confined body of liquid, causing a circulation of said liquid in its confined state during the bodily revolution of same, passing a stream of gas into said body of liquid for admixture with said revolving and circulating liquid, compressing by centrifugal pressure said mixture of gas and liquid, and retarding the flow of said mixture during its bodily revolution to cause a separation of the gas from the liquid under centrifugal pressure.
16. A rotary compressor for gases comprising a shell adapted to be rotated, means for supporting same, a liquid in said shell, means for rotating said shell, means for continuously circulating said liquid in said shell during its rotation whereby said liquid will flow with varying speeds in different portions of said shell and under varying pressures, means for drawing a plurality of variable streams of gas into said shell by means of Venturi effect, said gas-drawing means being located near the center of said shell at one end thereof at a point of comparatively decreased pressure in said fluid, the circumferential velocity of said rotating motion of said liquid being utilized in gradually compressing said mixture as it circulates and moves toward the periphery of said revolving shell, means at the periphery of said shell for changing the direction of the flow of said mixture and retarding its speed by enlarging a portion of the passage within the shell to cause a complete separation of the compressed gas from said liquid, means to prevent readmixing of said separated gas with said separated liquid, means for permitting the discharge of the compressed gas from the shell, means arranged for returning all liquid freed of the compressed gas to the central part of shell for continuous operation, means for arresting the rotating movement of said gas-free liquid as it circulates and moves toward the center of the shell, whereby the circulation

is facilitated, and means for automatic supply of the liquid into said shell.

17. A rotary compressor for gases comprising a revolving shell mounted on a hollow rotatable shaft, bearings supporting said shaft, said bearings being formed integrally with a stationary hollow base therefore, a liquid within said shell, a storage supply of the liquid in said stationary base, tubular means for automatically supplying the liquid from said storage into said shell having a central annular chamber and a peripheral annular separating chamber, both of said chambers having a plurality of vanes and partitions, a plurality of curved radial passages at one end of said shell, said passages adapted to cause a rotation of said liquid with said shell, a plurality of shorter, substantially radial, passages at the other end of the shell, both sets of said passages connecting both of said annular chambers to form a complete circuit in which the liquid circulates within said shell, said central annular chamber being arranged as a Venturi orifice consisting of a plurality of passages, a plurality of gas inlet passages for injecting a plurality of intermittent streams of gas into said shell to create a mixture of gas bubbles in said liquid, a plurality of gas vents leading from said separating annular chamber to said hollow shaft for discharging the compressed gas therethrough, a stationary-blade wheel having curved channels therein, said wheel being mounted within said shell and adapted to retard the rotation movement of the gas-free liquid, means for cooling said liquid, means for cooling the compressed gas, means for controlling the quantity of injected gas, means for automatically stopping the admission of gas at determined higher pressures than required, and means to arrest the circulation of the liquid and the compression of the gas without stopping the rotation of compressor, for the purpose set forth.
18. An apparatus for compressing gas comprising a centrifugally acting rotary cylindrical casing, a liquid in said casing, a plurality of gas inlet passages leading into the central part of said casing, a series of gas ducts leading from an enlarged peripheral portion of said casing to a main gas discharging pipe provided with a non-return check valve, said casing having curved passages adapted to transmit energy to the mixture of gas and liquid and to gradually increase the rotating velocity of said mixture toward the outer periphery of said casing, said passages being adapted to deliver the separated liquid in a direction, which has a radial component across an annular space to curved passages of a blade wheel, a blade wheel located within said casing and equipped with curved vanes, said vanes being coaxial with said wheel and operable to

stop or gradually retard the rotating velocity of said energized liquid, said blade wheel being adapted for independent rotation or stationary position as required, and a hand-wheel for controlling said blade wheel, said blade wheel discharging said liquid back into said casing toward its center, said casing and said blade wheel both having a series of annular curved passages arranged adjacent to each other and comprising a complete circuit of passages in the form of a gyratory ring in which said liquid is circulated.

In witness whereof I affix my signature.
